UNITED STATES PATENT OFFICE.

CHARLES HIRAM FULSON, OF TRENTON, TENNESSEE, ASSIGNOR TO THE AMERICAN COTTON OIL COMPANY, OF NEW YORK, N. Y., A CORPORATION OF NEW JERSEY.

PRESS MAT FOR OIL PRESSES.

1,414,693.

Specification of Letters Patent.

Patented May 2, 1922.

Application filed April 23, 1921. Serial No. 463,926.

To all whom it may concern:

Be it known that I, CHARLES H. FULSON, residing at Trenton, in the county of Gibson, State of Tennessee, have invented certain new and useful Improvements in Press Mats for Oil Presses; and I do hereby declare the following to be a full, clear, and exact description of the invention, such as will enable others skilled in the art to which it appertains to make and use the same.

This invention relates to improvements in oil presses, and more particularly to improvements in compression boxes or press mats for use in such oil presses.

In hydraulic presses for the pressing of oil from cottonseed, etc., press mats or plates are commonly provided, of a construction intended to promote the drainage of oil during the pressing operation. The drainage channels in such mats or plates tend to become clogged, after a certain period of use, and the satisfactory pressing of the oil is interfered with.

The present invention provides an improved construction of press mat which can be easily and readily cleared in case of clogging, which is simple in construction and operation, which provides for the free drainage of oil from the press cake, which causes a minimum of wear and strain upon the press cloth, and which enables the capacity of the presses to be materially increased by the use of press cakes of increased thickness.

The invention will be further described in connection with the accompanying drawings showing the preferred embodiment thereof.

In the accompanying drawings;

Fig. 1 is an end view of two sections of an oil press embodying the invention;

Fig. 2 is a side view of part of one of the sections; and

Fig. 3 is an enlarged detail view showing one of the grooves and bars.

In Fig. 1 the upper section of the press is shown with the bars removed from the longitudinal grooves, while the lower section of the press shows the bars in part in end elevation and in part in cross section.

It will be understood that the oil press is a hydraulic press, such as is commonly used in pressing oil from cottonseed, and that the different sections are supported and arranged in the usual way.

The sections illustrated are made up of the base plate 1, having depending side

flanges or members 2 forming the sides of the different compartments of the press. Supported by these base plates are the press mats which are made up of the base member 3, having longitudinal grooves 4 therein spaced apart at intervals and longitudinal bars 5 arranged in these grooves, with their upper surfaces even with the upper surface of the base members 3. These bars 5 are somewhat narrower than the grooves in which they are arranged, and they have longitudinal channels 6 in their sides forming oil channels for the escape of oil during the pressing operation. The bars 5 may be slightly narrower at their top than at their bottom, as illustrated in Fig. 3, so that they will be spaced away from the sides of the grooves at their tops to provide narrow longitudinal slots leading to the longitudinal oil channels 6. The arrangement is such that two slots are provided by each bar, one on each side, so that there are twice as many slots and longitudinal channels as there are grooves 4 and bars therein.

The bars 5 are turned at their ends, as illustrated at 7 in Fig. 2. These turned ends limit the endwise movement of the bars in the grooves and facilitate the raising of the bars for clearing the slots and channels as they become clogged. By grasping the end of each bar by hand or by a tool, the operator can readily raise the bar from the slot and clear the grooves 4 from obstruction. In case the mere raising of the bar does not suffice for this purpose, the bar may be drawn lengthwise for its entire length and then replaced. Instead of raising these bars by hand, a tool may be used which will raise the ends of the entire series of bars of any one press mat at the same time. In case a bar sticks in the groove, it can be readily loosened by means of the projecting end 7.

The base member 3 of the press mat may be of similar construction to the base plates commonly used in oil presses; but the arrangement of the bars therein in the manner above described, makes the press mat as a whole one of improved construction. The thickness of the mat is reduced by the omission of any plates or projections on top of the base member, so that the thickness of the mat is that of the base member itself. The cake space in the press is correspondingly increased, thus materially increasing the size of the cake which can be introduced and cor-

respondingly increasing the capacity of the press without any other change therein than the change in the construction of the press mats.

5 The individual grooves 4 and bars therein are entirely independent of each other, so that the individual bars may be removed and replaced independently of each other.

10 The ease with which the improved mats of the present invention can be cleared from obstruction enables the press boxes to be kept in regular and constant operation without interruption for the clearing operations.

15 Where the base members 3 do not have a width equal to the distance between the side members 2, the corners of the members may be removed and sections or side pieces 8 secured thereto by screws or otherwise.

20 It will be noted that the bars 5 are not fastened in place in the grooves, so that they are readily removable for clearing obstructions, while they are nevertheless properly spaced in the grooves longitudinally by means of the bend ends 7.

25 The improved press mats of the present invention may be used in presses of coramond construction, in place of the press boxes commonly used. So also, press mats now in use, if they are provided with longitudinal 30 grooves, may be converted into the improved press mats of the present invention by placing in the longitudinal grooves bars of appropriate length and cross section, to give a construction similar to that above described and illustrated in the accompanying drawings.

35 The increased facility with which the press mat of the present invention can be kept cleared of obstruction, enables the loss 40 of oil, due to such obstruction, to be reduced, with corresponding increase in the oil production of the press.

I claim:

1. A press mat for oil presses made up of a base member with longitudinal grooves and 45 bars in said grooves having their upper surfaces even with the upper surfaces of the base member, said bars being spaced away from the sides of the grooves to provide longitudinal slots and channels for the 50 escape of the oil.

2. A press mat for oil presses comprising a base member having longitudinal grooves of substantially rectangular section and bars in said grooves having their upper surfaces 55 even with the upper surface of the base member, said bars having longitudinal grooves in their sides and being narrower than the grooves at their upper edges to provide slots leading to said longitudinal channels. 60

3. A press mat for oil presses comprising a base member having longitudinal channels and bars in said channels forming therewith longitudinal passages for the escape of 65 oil, said bars having projecting ends by means of which they may be removed from the grooves to permit clearing of the oil channels from obstructions.

4. A press mat for oil presses comprising 70 a base member having longitudinal grooves therein, bars in said grooves having longitudinal recesses in their sides forming longitudinal oil passages, said bars being narrower than the grooves at their upper 75 edges to provide slots communicating with the oil passages, and said bars being provided with projections at their ends by means of which the bars may be raised for clearing the oil channels from obstructions 80 and by means of which the bars may be longitudinally positioned in the slots.

In testimony whereof I affix my signature.
CHARLES HIRAM FULSON.
